REVOLVING DOOR

Edmund Peremi, Manhasset, and Charles Kish, Elmhurst, N. Y., assignors to General Bronze Corporation, Long Island City, N. Y., a corporation of New York

Original application May 26, 1932, Serial No. 613,602. Divided and this application August 5, 1935, Serial No. 34,846

10 Claims. (Cl. 20—18)

This invention relates to revolving doors. It has for its object the provision of improved constructions for mounting the leaves of the door upon the central column in such manner that the leaves may be readily folded either to permit the door to be moved to one side of its enclosure when not being used, or to permit the leaves to fold or collapse in case of emergency. It is a particular object of the invention to mount leaves in such a way that they will not sag or get out of alignment, either when in radially operative position or when collapsed. Owing to the positive and firm pivotal support of the door leaves, and to the fact that sagging and twisting of the door leaves are prevented when they are being folded, the pivoting of the door leaves is easily accomplished without danger of the leaves becoming jammed. It is also possible to make the door with close clearances between the parts, particularly between the inner vertical edges of the leaves and the door column, without danger of binding between the surfaces at those points. In this way a weather tight door is secured.

Other objects and advantages of the invention will appear from the description of certain preferred embodiments thereof, chosen to illustrate the principles of the invention.

The present invention is a division of our co-pending application Serial No. 613,602, filed May 26, 1932, for Revolving doors, now Patent No. 2,010,825.

In the accompanying drawings which illustrate such preferred embodiments:

Figure 1 is a front elevation of a door, showing the door enclosure in section;

Figure 2 is a plan view of the door with the ceiling and parts above omitted, and showing the door enclosure in horizontal section;

Figure 3 is a view partly in elevation and partly in central vertical section of the upper part of one form of door;

Figure 4 is a similar view showing the lower part of the same door;

Figure 5 is a fragmentary view partly in section showing the central part of the same door;

Figure 6 is a vertical sectional view of the central part of the door column shown in Figure 5, the section being at right angles to the section shown in Figure 5;

Figure 7 is a fragmentary view in elevation of the portion of the door column shown in Figures 5 and 6;

Figure 8 is a horizontal sectional view taken on line 8—8 of Figure 4, looking upward, showing two of the door leaves folded;

Figures 9 and 10 are vertical sectional views taken on lines 9—9 and 10—10 respectively of Figure 4;

Figure 11 is a vertical sectional view taken on line 11—11 of Figure 3, on a larger scale;

Figure 12 is a horizontal sectional view of the side portion of a door leaf showing a construction of weather stripping;

Figure 13 is a similar view showing a modified form of weather stripping;

Figure 14 is a view partly in elevation and partly in central vertical section showing the lower part of another modified form of revolving door;

Figure 15 is a horizontal section taken substantially on line 15—15 of Figure 14, looking upward;

Figure 16 is a horizontal sectional view on line 16—16 of Figure 14;

Figure 17 is a view similar to Figure 14 showing another modified construction of door; and

Figure 18 is a horizontal sectional view taken substantially on line 18—18 of Figure 17, looking upward, showing two of the door leaves folded.

Referring to the drawings in detail, particularly to Figures 1 and 2, revolving doors of the character involved in the present invention comprise a central column 70 which is mounted to rotate about a vertical axis and which is suspended in a suitable manner in the door enclosure 41, and which carries a plurality of door leaves 54.

Preferably the column 70 is suspended from a trolley (not shown) which is mounted to travel on a horizontal track (not shown) extending across the top of the door enclosure and above the ceiling 44 thereof. The latter is provided with a slot 45 through which the door column passes. At the bottom of the door column is a retractable pivot bolt which is received in a socket located at the center of the floor of the door enclosure, a second socket being preferably provided near the side of the door enclosure to receive the pivot when the door is collapsed and moved to one side.

Mounted on the column 40 are the door leaves 54, usually four in number, these leaves being attached to the column by suitable hinge mechanisms, preferably located near the upper and lower ends of the leaves. While four leaves are illustrated and four leaves are usually used in these doors, a different number of leaves may be utilized if the layout of the building requires.

For instance three leaves are sometimes employed, which leaves would be mounted in a manner similar to that described. These hinge mechanisms permit the door leaves to be folded so that the door may be collapsed and moved to one side.

50
55

of the door enclosure as indicated in dotted lines in Figure 2. As will be understood, one or more of the door leaves may be folded, and in some instances the door leaves may be folded two and two, so as to extend in diametrically opposite positions from the central column, in a well understood manner. Suitable means are provided for retaining the door leaves in spaced radial position during operation, such for instance as 10 the chains 60. These chains are preferably releasably secured to the leaves in any suitable manner, for instance in one of the manners shown in our applications for patent, Serial No. 585,270, and Serial No. 592,004. By the use of suitable 15 releasable connections between the door leaves, the latter may either be released manually when it is desired to collapse the door and move it to one side, or such releasable connections will give way upon the application of excessive pressure to 20 opposite leaves of the door, such as may occur in the case of a panic, and thereby permit free passage through both sides of the door.

In Figures 3 to 10, inclusive, 70 is a supporting tube which has fixed near its upper and lower 25 ends discs 151. Each of these discs has in its lower face a circumferential guide groove or track 152, which preferably is of polygonal form with rounded corners. Also formed in the lower face 30 of each disc are four radial guide grooves 155 which intersect the circumferential guide grooves 152. Each of the leaves 54 is provided with upper and lower hinge fittings 156 and 157 respectively and each of these fittings carries two pins 158 and 159. Each of the pins 158 has pivoted on its 35 end a pivot slide or supporting block 160, the outer face 161 of which is curved preferably to a radius equal to the radius of the outer wall of the round cornered portions of the circumferential guide groove or track. The inner face 162 of each 40 block is preferably flat so that the blocks are narrower at the ends than in the center. The blocks are of such form that they will travel around the round cornered polygonal grooves, as clearly shown in Figure 8. When the door 45 leaves are in radial position, the faces of these blocks will seat firmly against the outer walls of the round cornered portions of the circumferential grooves, spanning the grooves 155, as shown at the right hand side of Figure 8. The blocks 50 at 160 and pivots 158 thus provide means for supporting the leaves firmly and preventing sagging. Each of the pins 159 carries at its end a guide block 165 which slides in one of the radial guide 55 grooves 155. These blocks 165, sliding in the radial grooves, serve to constrain the leaves to move in definite paths when being closed or opened, and prevent the tops and bottoms of the leaves from getting out of alignment. Blocks 160 are preferably made of such length that the adjacent ends of the blocks on the two inner leaves 60 will come into contact when the leaves are folded into parallelism, thereby stopping and assisting in supporting these leaves in such parallel position. To permit the leaves to be closely folded, 65 as shown at the left hand side of Figure 8, each of the leaves is provided with recesses 170 to receive the projecting portions of the corresponding hinge discs. Suitable flap means mounted in the hinge fittings are provided for closing these recesses 70 when the door leaves are in radial position, so as to prevent the passage of drafts. As shown in Figures 3, 4, 8, 9 and 10 a single flap member 171 is provided centrally in each recess, such flap member being hinged along its lower edge, as 75 shown at 172, and having at one end a project-

ing lug 173 which is engaged by the flat head 174 of a plunger 175 mounted in a recess in the hinge fitting, and urged upwardly by a spring 176. When the flap is pushed to one side or the other, by engagement with the edge of the disc 151, as 5 shown in Figure 8, the projection 173 will force down the plunger 175 and upon release of the pressure on the flap, the spring 176 will raise the plunger and return the flap to vertical position.

In the construction above described, the supporting tube 70 of the central door column is enclosed within a sleeve 180 extending between the upper and lower discs 151, the sleeve 180 being of smaller diameter than the column sleeves shown in the modifications described above, and having 15 concave recessed portions 181 depressed therein, the inner surfaces of the bottoms of which contact with the surface of the supporting tube 70, thereby giving added strength and assisting in preventing accidental deformation of the sleeve. 20

In Figures 5, 6, and 7, a construction for locking the operating device for the central door pivot and for the trolley latches is illustrated, this locking device being applicable to any of the door constructions shown or other similar door constructions. As will be understood the door has a central pivot 46 at the bottom of the column and a latch operating head 190 at the top of the column. These two members are connected by rods 191 with a slide 192 located at a convenient point 30 in the door column. The slide 192 has a hole 193 therein adapted to receive a suitable key or tool 194 (Fig. 6), which may be inserted into the hole through a slot 195 in the sleeve 180 and a slot 196 in the supporting tube 70. A sliding 35 shield 197 is preferably provided for closing all but the lowest part of the slot 195, the shield being mounted to slide between the tube 70 and the sleeve 180 and being limited in its movement by the engagement of a flange 198 on the back of the shield with the head of a screw 199 inserted in the tube 70. Attached to the side of the tube 70 opposite to the slot 196 is a block 200 having two recesses therein, in which are mounted respectively locking pins 201 and 202, each of which is 40 normally urged inwardly by a spring 203. When the slide 192 is in its lower position, as shown in Figure 6, the locking pin 201 will enter the hole 193 and prevent the slide 192 from moving upwardly, thereby positively locking the bottom pivot of the door in its socket. When it is desired to collapse and shift the door to the side of its enclosure, the key 194 is inserted in the hole 193 and pushed against the end of the pin 201, thereby pushing said pin out of the hole 193, and permitting the slide 192 to be moved upwardly by means of the key. When the slide has been moved to its upper position with the pivot and trolley latch disengaged, the hole 193 is opposite to the locking pin 202 and upon the withdrawal 50 of the key 194 this pin will snap into the hole of the key 194 this pin will snap into the hole 193 and retain the slide in raised position until the key is again inserted.

Figures 9 to 13 inclusive show a suitable construction of weather strip which may be used with any of the revolving doors shown, or with other revolving door constructions. Figures 9 and 10 show the bottom strip for the door, comprising a flexible strip 210 of felt, rubber, or the like mounted in the bottom channel of a door leaf by means of the clamping strips 211 which may be of wood, metal, or other suitable material. Figure 11 shows a construction of weather strip at the top of the door leaf, comprising a strip 215 of felt, rubber or other suitable flexible ma-

material clamped between a pair of serrated jaws 216 and 217. The jaw 216 is formed on the channel member 218, fixed to the top rail of the door leaf, while the jaw 217 is formed on a curved strip member 220 which is removably attached to the opposite flange of the channel member 218 from that which carries the fixed jaw 216. The removable jaw strip 220 has a rib 221 on its inner edge which bears in a groove 222 in the side of the channel member 218, and clamping screws 223 are provided by which the strip 220 may be drawn towards the flange of the channel member 218 and thereby firmly clamp the weather strip between the serrated jaws. This construction holds the weather strip very firmly and at the same time permits its adjustment in case of wear or replacement. Figure 12 shows a similar construction applied to the weather strip at the side of the door leaf which engages the inner surface of the door enclosure 41. The weather strip at the side of the door leaf preferably comprises a tapered rubber strip 225 which has attached to its edge a wear strip 226 of felt composition, rubber or the like.

Figure 13 shows a modified construction of weather strip at the side of the door leaf in which a tapered composition, rubber, felt or the like, weather strip 230 is employed which carries a wear strip 226 and which has an enlarged base 231 which is received in a groove 232 formed in the edge of the door leaf. One wall 233 of the groove is made removable so as to permit insertion and removal of the weather strip.

In Figures 14, 15 and 16 another form of hinge construction for securing the door leaves to the central door column is illustrated. As shown in these figures, the supporting tube 70 of the door column has fixed to its lower end a disc 240, it being understood that a similar disc, not shown, is secured to the upper end of the tube. The disc 240 is of somewhat polygonal outline and has at each of the corners a vertical notch 241. In the top face of the disc 240 is an annular groove or track 242 and in the lower face of the disc are cut four radial grooves 243, the walls of which merge into the diverging curved surfaces 244, as shown in Figure 22, so as to form what may be described as flaring mouths for the grooves. Mounted below the disc 242 and fixed thereto is a cross-member 250 having four short arms, in the end of each of which is a notch 251. The door leaves 54 are each provided with a lower hinge fitting 255 and with a similar upper hinge fitting not shown. Mounted in each hinge fitting is a pin 256 which carries a guide roller 257 travelling in the annular guide groove or track 242. Each hinge fitting also carries a pin 260 which is adapted to travel in one of the radial grooves 243 and which follows one of the diverging curved surfaces 244 when the door leaf is folded, as shown at the left hand side of Figure 15. The hinge fittings are also provided with lugs 263 adapted to engage with the proper notches 251 when the leaves are fully collapsed, so as to support the leaves against sagging in that position. The adjacent lugs 263 on the hinge fittings of the inner pair of leaves are adapted to contact when the leaves are folded into parallel position so as to stop the leaves in that position. Each leaf is firmly supported and caused to move in a constrained path, by the engagement of rollers 257 on the pins 256 at the top and bottom of each leaf, in the corresponding annular grooves in the discs and by the engagement of the pins 260 in the radial grooves 243.

When the leaves are fully folded, one of the lugs 263 on each of the outer leaves, the pins 260 of which have left the radial grooves 243, will engage with one of the notches 251 and thereby firmly support such leaves against sagging. As in the forms of door described above, the supporting tube 70 of the door is enclosed within a suitable sleeve 270, as shown in Figure 16. In order to enable the leaves to fold closely they are slotted as indicated at 275, so as to receive the edges of the discs 240. To close the outer part of such slots when the leaves are in radial position, spring flaps 276 are provided which are pivoted on vertical pivots 277. When the leaves are in radial position, the ends of these flaps 15 extend into the grooves 241.

Another form of door hinge construction is shown in Figures 17 and 18 which is similar in many respects to the construction shown in Figures 14 to 16. In this construction upper and lower discs are fixed to the supporting tube 70, the lower disc only being shown at 280. Each of these discs has a guide groove or track 281 in its upper face, the groove being formed of four arc shaped sections as indicated in Figure 18, adjacent sections joining in the cusp-like intersections 292.

In the lower face of the disc are formed radial grooves 293, the walls of which merge into outwardly diverging walls 294 so as to form flaring mouths for the grooves. Fixed in the lower face of the disc are four bearing pins 295. The door leaves are provided with hinge fittings 296 which carry pins 297 on the ends of which are mounted rollers 298 which travel in the circumferential guide grooves 294. The hinge fittings also carry pins 300 which travel in the radial grooves 293, and which, when the door leaves are completely folded as shown at the lower left side of Figure 18, travel on the curved surfaces 294. The hinge fittings 296 are also provided with lugs 303 adapted to engage with the proper pins 295 when the door leaves are fully collapsed so as to support the leaves against sagging when in that position. The adjacent lugs 303 on the inner pair of leaves are adapted to contact when the leaves are folded into parallelism, and thereby stop the leaves in that position. To prevent leakage through the slots in the leaves which are formed to clear the edges of the discs 290, spring flaps 305 are provided.

While we have illustrated and described in detail certain preferred forms of our invention, it is to be understood that changes may be made therein and the invention embodied in other structures. We do not, therefore, desire to limit ourselves to the specific constructions illustrated, but intend to cover our invention broadly in whatever form its principle may be utilized.

We claim:

1. In a revolving door, a central supporting column, a plurality of door leaves, members mounted on said column each provided with a generally square track, rounded at the corners and with radial tracks which intersect the square track at the corners, guide members attached to the leaves and travelling in said generally square tracks and guide members attached to the leaves and travelling in said radial tracks.

2. In a revolving door, a central supporting column, a plurality of door leaves, members mounted on said column each provided with a generally square track, rounded at the corners and with radial tracks which intersect the square track at the corners, blocks pivoted to the leaves

and arranged to slide in said generally square tracks and guide members attached to the leaves and travelling in said radial tracks.

3. In a revolving door, a central supporting column, a plurality of door leaves, discs pivoted to said leaves and each having a generally square track, rounded at the corners and with radial tracks which intersect the square track at the corners, blocks pivoted to said leaves and arranged to travel in said generally square tracks, and guide members attached to said leaves nearer to the inner edges thereof than the points on the leaves at which said blocks are pivoted, said guide members being arranged to travel in said radial tracks.

4. In a revolving door, a central supporting column, a plurality of door leaves, discs mounted on said column having circumferential tracks therein and also being provided with radial grooves whose walls are parallel for a substantial distance and then separate to form flaring mouths, a single supporting member on each leaf arranged to travel in the circumferential track of one of said discs and guide pins on the leaves arranged to travel into and out of said flaring mouths, radial grooves when the leaves are opened or folded.

5. In a revolving door, a central supporting column, a plurality of door leaves, discs mounted on said column having circumferential tracks therein and also being provided with radial grooves terminating in flaring mouths, supporting members on the leaves arranged to travel in said circumferential tracks and guide pins on the leaves arranged to travel into and out of said flaring mouths, radial grooves when the leaves are opened or folded, and supporting members fixed with relation to said discs formed to inter-engage with lugs on the inner faces of the outermost leaves when the leaves are folded into parallel positions.

6. In revolving door construction, a central column, a plurality of door leaves pivotally mounted thereon, said door leaves having recesses extending therethrough to clear portions of the mechanism when said leaves are folded, flaps pivoted centrally in said recesses, lugs projecting from the ends of said flaps, and spring pressed plungers engaging said lugs for yieldingly maintaining said flaps in planes parallel with the planes of the respective leaves on which the flaps are mounted.

7. In revolving door construction, a central supporting column, a plurality of door leaves carried thereby, a retractable central door pivot mounted at the lower end of said column, a slide in said column operatively connected to said pivot, 5 said slide having a transverse hole therethrough, and locking means for said slide comprising upper and lower latch pins mounted in said column, one or the other of which is adapted to engage in the hole in said slide and to be released from said hole by the insertion of a key through the hole. 10

8. In a revolving door, a central supporting column, a plurality of door leaves, members mounted on said column provided with annular tracks extending continuously around the column 15 and with radial slots which intersect the annular tracks at equally spaced intervals, guide members attached to the leaves and travelling at all times in said annular tracks and guide members attached to the leaves and travelling in said 20 radial slots.

9. In a revolving door, a central supporting column, a plurality of door leaves, members mounted on said column provided with annular tracks extending continuously around the column 25 and with radial slots which intersect the annular tracks at their points of maximum radius, guide members attached to the leaves and travelling at all times in said annular tracks and guide members attached to leaves and travelling 30 in said radial slots.

10. In a revolving door, a central supporting column, a plurality of door leaves, members mounted on said column, each provided with an annular track of non-circular form having portions of maximum radius and portions of a decreased radius, and with radial tracks intersecting said annular track at its points of maximum radius, blocks pivoted to said leaves and arranged to travel in said annular track and stand in the 40 said annular track at said positions of maximum radius when the leaves are in radial position and to stand in said positions of decreased radius on said annular track when the said leaves are 45 folded, and guide members attached to said leaves nearer to the inner edge thereof than the points on the leaves at which the said blocks are pivoted, said guide members being arranged to travel in said radial tracks.

EDMUND PEREMI.
CHARLES KISH.
